(57) CLAIM

The ornamental design for a headrest, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front, left side, and top perspective view of a headrest showing the new design;

FIG. 2 is a top plan view thereof;

FIG. 3 is a front elevation view thereof;

FIG. 4 is a right side elevation view thereof;

FIG. 5 is a front, left side, and top view thereof with the center portion removed for clarity of disclosure;

FIG. 6 is a top plan view thereof;

FIG. 7 is a front elevation view thereof;

FIG. 8 is a right side elevation view thereof;

FIG. 9 is a front, top, left side elevation view of the central portion of the headrest removed from the outer portion for clarity of disclosure;

FIG. 10 is a top plan view thereof;

FIG. 11 is a front elevation view thereof; and,

FIG. 12 is left side elevation view thereof.

1 Claim, 12 Drawing Sheets
